US00D782220S

(12) **United States Design Patent** (10) Patent No.: **US D782,220 S**
(45) Date of Patent: **** Mar. 28, 2017**

(54) **PILLOW**

(71) Applicant: **DG International Holdings Limited**,
London (GB)

(72) Inventors: **Simon Little**, Enfield (GB); **Benjamin Atkinson**, Chipperfield (GB)

(73) Assignee: **DG International Holdings Limited**,
London (GB)

(**) Term: **15 Years**

(21) Appl. No.: **29/553,871**

(22) Filed: **Feb. 5, 2016**

(30) **Foreign Application Priority Data**

Aug. 7, 2015 (EM) 002751636

(51) LOC (10) Cl. **06-09**

(52) U.S. Cl.

USPC **D6/601**
